WILLIAM J. MILLER, OF SWISSVALE, PENNSYLVANIA

MEANS FOR REMOVING EXCESS OF MATERIAL IN SHAPING POTTERY WARE

Application filed January 5, 1927. Serial No. 159,143.

This invention relates to a means for removing excess material in the production of pottery ware, and the principal object of the same is to provide for the automatic removal 5 of the excess plastic material or clay which accumulates as a result of the profiling or shaping operation.

The means employed in general consists in a conduit member which is mounted in co- 10 operative relation with the profile and has an inlet port so disposed that the excess material will be forced thereinto by the pressure set up between the profile and mold, the latter preferably being of the rotative type 15 and the profile stationarily mounted with respect to the mold, means being provided for conveying the excess material from the conduit member.

With the foregoing and other objects and 20 advantages in view, the invention consists in the preferred construction and arrangement of the several parts which will be more fully hereinafter described and claimed.

In the drawings Fig. 1 is a vertical section 25 on the line 1—1 of Fig. 3, showing sundry parts in elevation.

Fig. 2 is a plan view, on a smaller scale, of one form of means for removing excess of material in profiling, as applied to shallow 30 ware, such as saucers, plates and the like, showing the channel or casing of the tangential conveyor, which is hereinafter described partly in section.

Fig. 3 is a fragmentary sectional view on 35 the line 3—3 of Fig. 1.

Fig. 4 is a central vertical section of another form of means for removing excess of material in profiling deep ware, such as cups and the like.

Fig. 5 is a plan view of a means for crushing the removed material which is herein- 40 after described.

Fig. 6 is a plan view of a modification of the detail shown in Fig. 5.

Fig. 7 is a plan view of another modifica- 45 tion of the said detail.

Fig. 8 is a plan view of the preferred form of said detail.

Fig. 9 is a fragmentary sectional view on 50 the line 9—9 of Fig. 8.

Fig. 10 is a detail, on a larger scale, of one of the rollers shown in Fig. 7.

Like numerals refer to like parts throughout the several views:

11 designates a chuck of either a standard 55 jigger or a reciprocating jigger, such as described in my copending application for jigger for use in the manufacture of articles from plastic materials, filed October 25, 1926, Serial No. 143,994; and 12 designates a mold, 60 supported by said chuck under a profile 13, which is shown in Fig. 3 as having thereon a reinforcement 13a. The profile 13 is adjustably secured to a holder 14 by means of bolts or screws 15; vertical slots 16 in the profile 13 and horizontal slots 17 in the holder 14 which permit universal adjustment of the profile 13 with relation to the holder 14 and the charge of material 18 on 65 the mold 12. 70

The profile 13 is shown in Figs. 1 and 3 as having connected thereto a bracket 19 by means of screws 20.

Vertical slots 21 in the bracket 19 and horizontal slots 22 in profile 13 permit universal 75 adjustment of bracket 19 with relation to the profile 13 and to the charge of material 18 on mold 12.

The bracket 19 terminates at the lower end 80 thereof in a conduit member 23, which is shown in Fig. 3 as made in one with bracket 19, for enclosing part of the periphery of the inner half of a spiral or helical screw or conveyor 24, leaving at the underside thereof an 85 opening 38, lengthwise said half, and enclosing the entire periphery of the greater part of the outer half of screw 24, leaving an opening 39 at the outer end of the conduit member 23 at the underside thereof, as shown 90 in Fig. 1.

The screw 24 is shown as held in a plane, which is substantially parallel to the profile 13, over material 18 by means of a shaft 25, which has its ends journalled in bearings 26 95 and 27, which are formed in the end walls 28 and 29 respectively of conduit member 23.

A cylindrical groove 81 in the forward side of the profile 13 serves to enclose the rear part of the screw 24 at the inner end thereof, 100

whereby the lower or acting part of said screw is brought nearer the profile 13.

The screw 24 is shown as left handed in Fig. 1, and its direction of rotation is indicated by an arrow in Fig. 3 as counterclockwise.

A right hand screw may be employed and rotated in a clockwise direction, if desired; in the latter case the conduit 23 may be dispensed with and the screw 24 operated as a propeller, to remove the surplus material on the mold 12 and on the disc 61, which is hereinafter described, as soon as it reaches the screw 24; in the modification shown in Fig. 1 the action of the inner end of the screw 24 under the inner end of the conduit member 23, which is shown as open at the underside thereof, will tend to transfer and pile up the surplus material from the mold 12 into the inner end of said conduit member until it will fill up the inside of the conduit member, which, with the groove 81 in profile 13 encloses or nearly encloses the inner end of the screw 24, whereupon said material will be forced into the outer end of conduit 23, which completely encircles the screw 24, and conveyed by the outer end of screw 24 to a trough 40 and channel 42 which are hereinafter described.

30 A sponge 30 is shown as kept in contact with the upper surface of material 18 by means of a bracket 31, which is adjustably connected to an extension 19a of bracket 19 by means of screws 32; vertical slots 33 in bracket 31 and horizontal slots 34 in extension 19a permit universal adjustment of bracket 31 and the sponge 30, carried thereby, with relation to said material.

40 The sponge 30 is normally kept moist or wet by means of a spray of fluid, preferably water, which may be suitably treated, from a nozzle 35 of a sprinkler 36. The intensity of said spray may be regulated by means of a valve 37 on said sprinkler.

45 The moisture from the sponge 30 is transmitted by contact and dribbling to the material 18 on mold 12, to soften the material, for facilitating the action of the profile 13 thereon; also to cause said material more readily to flow on the forward side of said profile 13, and to have the surplus thereof taken up by the screw 24, to be continually transferred thereby in a direction preferably from the apex of the mold 12 to the periphery thereof.

55 The opening 38 in the underside of the inner end of conduit 23 permits the excess of the material to pass into the zone of action of screw 24 in the conduit 23, to be propelled therethrough by said screw conveyor to a point near the outer end of the conduit 23, where the opening 39 permits the excess of material to be discharged therethrough into a substantially circular trough 40, which is shown as concentrically placed with relation

to the mold 12. It will be seen that the rotation of the mold forces the excess material into the opening 38 as it accumulates against the shaping edge portion of the profile, said portion preferably being shaped to form in conjunction with the mold a converging space into which the clay is forced by the rotating mold, the clay which is to be comprised in the ware being smoothed and compacted between the profile and mold and the excess clay passing into the opening 38.

70 When used with reciprocating jiggers, the trough 40 may be stationary with relation to the frame 44 of the machine and may be adjustably connected thereto by means of screws 82, which are shown in Fig. 1 of the drawings.

75 An annular space 83 is shown between trough 40 and chuck 11 with the mold 12 thereon, to provide room for molds of larger sizes than that of the mold 12, shown in Fig. 1. The annular space 83 may be spanned by a deflector disc 61, as shown in Fig. 1. The disc 61 may rest with the inner edge thereof on the mold 12, when the latter is in operative position under the profile 13, or, in reciprocating jiggers, with the outer edge thereof on said trough, when the mold is withdrawn lengthwise the axis thereof, as described in my above copending application.

80 When nonreciprocating jiggers are used, the disc 61 may be raised with the trough 40 each time when a mold is to be replaced in chuck 11; the trough 40 may then be adjustably connected to the profile 13 in the same way as the conduit 23; or independent means may be provided for raising said trough with the disc 61 thereon, when a mold is to be removed, and for lowering the same into position after a new mold has been placed into chuck 11; the disc 61 is then to be intercepted by the mold 12 and revolved therewith, whereby any surplus material on said disc may be thrown off by centrifugal force and transferred into the trough 40.

85 The trough 40 serves to receive part of the discharge from the conduit 23 and also the particles of material, which may be detached from the charge 18 and from the disc 61 and thrown off therefrom either by the screw 24, by centrifugal force, by the trimmer or otherwise.

90 A spray of water from a nozzle 41 of a sprinkler 45 serves to liquefy or semiliquify the material in said trough 40, to cause it to flow to the channel 42, which is shown in Fig. 2 as partly open and situated tangentially to said trough and in Fig. 1 as at a lower level than the latter. This channel may be embodied in the structure of said trough if desired. A suitable cover for the greater part of the length of the channel 42 may be provided, if desired.

95 A tangentially disposed screw conveyor 43

is placed in the channel 42, continually to remove said liquefied or semiliquefied waste material from said channel, to deliver it to any required destination, such as storage bins, where the waste material may be reclaimed in any suitable manner. The channel 42 may be ribbed as at 42^a in Fig. 1; the said conduit 23 may also be ribbed.

10 A sprinkler similar to 45 may be employed also for directing a spray of water to the top of the disc 61, to wash down therefrom any material, which may adhere thereto, into the trough 40, if desired.

15 The screw conveyor 43 is shown as right handed and single threaded, but it may also be left handed and multiple threaded, if desired.

20 The direction of rotation of the screw conveyor 43 is indicated by an arrow in Fig. 1 as counterclockwise; when a left hand screw conveyor 43 is employed, the direction of rotation may be clockwise instead.

25 A valve 46 is provided on sprinkler 45, for regulating the intensity of the spray from the nozzle 41 into the trough 40.

30 A water main 47 is provided, to supply water to the sprinklers 36 and 45, which are connected thereto by suitable fittings; said main has also connected thereto an additional sprinkler 48, which terminates in a nozzle 49, to direct a spray of water directly to the charge of material 18 on the mold; a valve 50 is provided on the sprinkler 48 to regulate the intensity of the spray delivered by the 35 nozzle 49.

35 The water main 47 has thereon also a valve 51, which is controlled by a cam 52, which is shown in Fig. 2 as mounted on a shaft or spindle 53, supported on suitable bearings 54, which may be mounted on the frame 44. The valve 51 serves intermittently to admit water to the sprinklers 36, 45, and 48.

40 A throttle valve 55 is also provided on the main 47, for manually closing and opening said main and for regulating the volume of water passing therethrough.

45 The conveyor shaft 25 is shown as having revolvably mounted thereon at the outer end thereof a material crushing and conveyor cleaning gear 56, which is shown in Figs. 1 and 2, in mesh with the end of screw conveyor 43, but the shaft 25 is not driven by the gear 56, which is loosely swivelled thereon and serves to disintegrate the material discharged by screw 24 and remove from the end of the conveyor 43 any particles of plastic material which may adhere thereto, thereby increasing the efficiency of said conveyor.

50 To enable the material crushing and cleaning gear 56 to be used for cleaning the entire length of the screw conveyor 43, the gear 56 may be disconnected from the shaft 25, or a separate gear 56^a provided, and mounted on an independent spindle 56^a, see Figs. 11 and 65 12, which may be mounted in a sliding frame

56^b and secured in position by collars 56^c, the frame 56^b having a dove-tail slidable mounting on the channel member 42. A crank gear or analogous member 56^d, rotatably mounted in a supporting bracket 56^e shown secured to one side of the channel member 42, may be used as an actuating means for the sliding frame 56^b, said gear 56^d being connected with said frame as by a connecting rod 56^f and pins 56^g and 56^h, a plurality of securing holes 56ⁱ being provided in the crank gear 56^d to permit adjustment of the throw of said gear. The gear 56^d is shown in mesh with a drive pinion 56^j, which may be driven from any suitable source. The sliding frame 56^b may also serve as a cover for the channel 42.

70 75 The shaft 25 may be driven by any suitable means, not shown.

80 85 For properly liquefying or semiliquefying the material, which finds its way into the trough 40, I provide a number of modifications of crushing and kneading or mixing devices, which are illustrated in Figs. 5, 6, 7, 8 and 9 of the drawings.

90 9 The modification shown in Fig. 5 spherical balls 57, which may be made of steel or any other suitable material, are placed in the trough 40, and are propelled by the screw conveyor 43 in the direction of the arrow in Fig. 5; the number of balls 57 may be larger than as shown in Fig. 5, and the weight as well as the impact of the balls 57 against the outer wall of said trough, which impact is due to the centrifugal force of said balls and the momentum thereof, will tend to crush the particles of material in the trough and to knead them or mix them with the water in said trough, thereby assisting in reducing the material to a fluid or semifluid condition.

100 105 In the modification shown in Fig. 6 one or more helical springs 58 are placed in trough 40, which is then provided with a cover, to mesh with the screw conveyor 43, which causes the coils of said spring or springs 58 both to rotate each around its axes and to slide with relation to the trough 40, thereby scraping off the particles of material, which may be adhering to the walls inside of said trough, and also crushing and kneading or mixing the same with the water in the trough.

110 115 The spring or springs 58 are kept by the trough cover from being thrown out of the trough by the conveyor 43.

120 125 In the modification shown in Fig. 7 rollers 59 are employed in place of the balls shown in Fig. 5; an enlarged view of the rollers 59 is shown in Fig. 10, and their action is similar to that of the balls 57, except that the rollers 59 have a larger surface in contact with the inside of the trough 40, which may be provided with a bottom, having a suitable flat or nearly flat shape, for said rollers to roll upon.

130 In the modification shown in Fig. 8, I provide centrifugal vanes 60, which are extending into the trough 40 from the annular or

conical deflector disc 61, to which said vanes may be connected; the disc 61 is shown in Fig. 1 of the drawings.

This modification is especially applicable to reciprocating jiggers, such as described in my aforesaid copending application for patent, but it may also be used with nonreciprocating jiggers.

In reciprocating jiggers the disc 61 comes into contact with the mold 12, when the latter is moved into operative position, as described in my above copending application, and said mold 12 imparts a rotary motion to said disc, whereby the vanes 60 are made to churn the contents of the trough 40 at a very high velocity, thereby thoroughly mixing the water with the plastic material in the trough to a liquid amalgam, especially if an abundance of water be allowed to flow into the said trough from the sprinklers 36, 45, and 48. The trough 40 may be provided with internal projections or other irregularities to assist in the disintegration of the material.

The vanes 60 are not in mesh with the screw conveyor 43, which is shown in Fig. 8 as disposed outside the circle of action of said vanes; the screw conveyor serves only to remove the contents of the channel 42, into which the fluid or semifluid mass from the trough 40 is discharged by gravity; the channel 42 is situated at a lower level than said trough, as in the modification shown in Fig. 1.

To prevent spilling of the contents of the trough when churned by the vanes 60, I prefer to have a modification 40a of the trough, which is covered, as shown in Fig. 9, where an annular lid 62 is shown as secured to the channel shaped trough 40a by means of bolts or screws 63.

40 When a profusion of water is allowed to flow into the trough 40a, the vanes 60 may act as an impeller of a centrifugal pump, and the screw conveyor 43 may then be omitted; the trough 40a with the lid 62 thereon should then have a spiral outline of a centrifugal pump casing, and water from the main 47 shall only be admitted thereto by the valve 51 and cam 52 during the time when mold 12 is in operative position, when the disc 61 with the vanes 60 is in motion.

The disc 61 is shown in Fig. 1 as raised by the mold above the inner edge of the trough 40, with the vanes 60 thereon extending into the said trough, without their touching the bottom or sides of the trough, to facilitate the revolution of the disc 61 with the vanes 60 thereon at the high velocities, at which the mold 12 is running, and to prevent the retardation of or undue frictional resistance to the motion of the mold.

When the mold 12 is withdrawn lengthwise its axis of revolution, as described in my above copending application, the disc 61 or the vanes 60 or both, are brought by the action of gravity into contact with the trough 40,

whereupon their rotary motion is gradually arrested by friction on said trough, and they are shortly thereafter brought to a standstill thereby.

In the modification shown in Fig. 4, where the lower end of a profile 79 is shown, I provide an angular conduit 66-67, which may be connected to the profile 79 in the same way as the conduit 23 in Fig. 1, and which has thereon two branches: a nearly vertical branch 66 and a substantially horizontal branch 67. A conveyor screw 68 is revolvably supported in position in the branch 66 by means of a shaft 69, which is journaled in the end walls 70 and 71 of the branch 66, and may have rotation imparted thereto by any suitable means. The action of screw 68 is similar to the action of the screw 24.

An opening 72 in the side of the branch 66 permits the surplus material from a charge 65 in a mold 64 to enter the branch under the influence of the profile 79, the upper part of which is not shown in Fig. 4 of the drawings. This action just mentioned takes place when the mold 64 is revolved by the chuck of the jigger, which is also omitted in Fig. 4.

The material, which passes into the branch 66, is then raised by screw 68 and discharged into the branch 67, where it is transferred in the direction from left to right in Fig. 4 by means of a conveyor screw 73, which is revolvably supported in position in the branch 67 by means of a shaft 74, which may be supported at one end thereof at a point, situated to the right of conveyor 73, by suitable bearings 85, which may be made in one with the ends of the branch 67, as shown in Fig. 4, or independently thereof, if desired.

An opening 75 in the underside of the branch 67 serves to discharge the material from said branch into any desired receptacle or carrier, to be taken to any desired destination.

A gate 76 is provided for the opening 75, whereby the discharge of the material therethrough may be regulated or shut off altogether.

Another discharge opening 84 may be provided at the end of the conveyor casing 67, if desired.

The angular conduit 66-67 may be adjustably connected to the profile 79 by means of a suitable bracket 80 thereon, in the same way as the conduit 23 is connected to the profile 13 in Fig. 1.

A suitable moistening device or sponge 77 is shown in Fig. 4 as supported by a bracket 78, which may be adjustably connected to bracket 80, and is employed for moistening the charge of material 65 in the mold 64 in Fig. 4.

Sprinkling devices similar to those shown in Fig. 1 may also be employed in the modification of my means for removing excess

of material in profiling, which is shown in Fig. 4.

Many other changes may be made in the details of my above removing means without departing from the main scope of my invention, and parts of my invention may be used without other parts.

I do not therefore restrict myself to the details as shown in the drawings; but I intend to include also all mechanical equivalents and obvious modifications of the same within the scope of my invention.

I claim as my invention, and desire to secure by Letters Patent:

15. 1. In a profiling apparatus a mold with a charge of material thereon, a profile, an automatic means for removing the excess of material, which is accumulating on the forward side of the profile during the operation 20 of profiling, a sponge, for moistening said charge, a bracket, adjustably connected to said profile for holding said sponge in position and an automatic means for spraying water onto said sponge during the operations 25 of profiling and removing the said excess of material.

2. In a profiling apparatus a mold with a charge of material thereon, a profile, an automatic means for removing the excess of material, which is accumulating on the forward side of the profile, a sponge, for moistening said charge, a bracket, for holding said sponge in position, a support for said bracket, adjustably secured to said profile, 35 vertical and horizontal slots in said support and in said profile, for universally adjusting said support and said bracket with relation to said profile and said charge, and an automatic means for spraying water onto said sponge during the operations of profiling and removing the said excess of material.

3. In a profiling apparatus a mold with a charge of material thereon, a profile, a trough encompassing the periphery of said mold, an automatic means for transferring the excess of material, which is accumulating on the forward side of said profile during the operation of profiling in a direction from the apex of said mold towards the periphery thereof, to be intercepted by said trough, and a means for conveying said material from said trough to a desired destination.

4. In a profiling apparatus a mold with a charge of material thereon, a profile, a trough, encompassing the periphery of said mold, an automatic means for transferring the excess of material, which is accumulating on the forward side of said profile during the operation of profiling in a direction from the apex of said mold towards the periphery thereof, to be intercepted by said trough, a means for spraying water into the said trough, to be mixed with said material therein, and a means for conveying the con-

tents of said trough to a desired destination.

5. In a profiling apparatus a mold with a charge of material thereon, a profile, a trough, encompassing the periphery of said mold, an automatic means for transferring the excess of material, which is accumulating on the forward side of said profile during the operation of profiling, in a direction from the apex of said mold to the periphery thereof, to be intercepted by said trough, a nozzle for spraying water into the said trough, to be mixed with said material therein, a water main, for supplying said nozzle, an automatic valve, for controlling the stream of water in said main, and a means for actuating said valve.

6. In a profiling apparatus a mold with a charge of material thereon, a profile, a trough, encompassing the periphery of said mold, leaving an annular space therebetween, to provide for molds of various sizes, a deflector disc, to span said space, said disc to rest at the inner edge thereof on said mold when the latter is in operative position, to revolve with said mold, an automatic means for transferring the excess of material, which is accumulating on the forward side of said profile during the operation of profiling in a direction from the apex of said mold towards the periphery thereof, to be intercepted by said trough, and a means for conveying said material from said trough to a desired destination.

7. In a profiling apparatus a mold with a charge of material thereon, a profile, a trough encompassing the periphery of said mold, an automatic means for transferring the excess of material, which is accumulating on the forward side of said profile during the operation of profiling in a direction from the apex of said mold towards the periphery thereof, to be intercepted by said trough, and a channel, disposed at a lower elevation than the latter, for conveying said material from said trough to a desired destination.

8. In a profiling apparatus a mold with a charge of material thereon, a profile, a trough, encompassing the periphery of said mold, an automatic means for removing the excess of material, which is accumulating on the forward side of said profile during the operation of profiling, in a direction from the apex of said mold towards the periphery thereof, to be intercepted by said trough, a channel disposed at a lower elevation than the latter, and a helical member for conveying said material from said trough to a desired destination.

9. In a profiling apparatus a mold with a charge of material thereon, a profile, a trough, encompassing the periphery of said mold, a helical member, for removing the excess of material, which is accumulating on the forward side of said profile during the operation of profiling, in a direction from the apex

of said mold towards the periphery thereof, to be intercepted by said trough, a channel, disposed at a lower elevation than the latter, a screw in said channel, for conveying said material from said trough to a desired destination, and a crushing and cleaning member, for disintegrating the material delivered into said channel by said helical member and for cleaning said screw.

10. 10. In a profiling apparatus a mold with a charge of material thereon, a profile, a trough, encompassing the periphery of said mold, a helical member for removing the excess of material, which is accumulating on the forward side of said profile during the operation of profiling, in a direction from the apex of said mold towards the periphery thereof, to be intercepted by said trough, a channel, disposed at a lower elevation than the latter, a screw in said channel, for conveying said material from said trough to a desired destination, and a gear in mesh with said screw, for disintegrating the material delivered into said channel by said member and for cleaning said screw.

11. In a profiling apparatus a mold with a charge of material thereon, a profile, a trough, encompassing the periphery of said mold, an automatic means for transferring the excess of material, which is accumulating on the forward side of said profile during the operation of profiling, in a direction from the apex of said mold towards the periphery thereof, to be intercepted by said trough, a means for introducing water into said trough, a means for mixing said material in said trough with said water and a means for conveying said mixture from said trough to a desired destination.

12. In a profiling apparatus a mold with a charge of material thereon, a profile, a trough, encompassing the periphery of said mold, an automatic means for transferring the excess of material, which is accumulating on the forward side of said profile during the operation of profiling, in a direction from the apex of said mold towards the periphery thereof, to be intercepted by said trough, a means for introducing water into said trough, vanes to revolve in said trough, for mixing said material in said trough with said water, a means for revolving said vanes during the operation of said mold, thereby mixing said material in said trough with said water, and a means for conveying said mixture from said trough to a desired destination.

13. In a profiling apparatus a mold with a charge of material thereon, a profile, a trough, encompassing the periphery of said mold, an automatic means for transferring the excess of material, which is accumulating on the forward side of said profile during the operation of profiling, in a direction from the apex of said mold towards the periphery thereof, to be intercepted by said trough, a

means for introducing water into said trough, a disc in contact with said mold, when the latter is in operative position, to be revolved by said mold, vanes on said disc, extending into said trough, for mixing said material in said trough with said water during the operation of said mold, and a means for conveying said mixture from said trough to a desired destination.

14. In a profiling apparatus a mold with a charge of material thereon, a profile, a trough, encompassing the periphery of said mold, an automatic means for transferring the excess of material, which is accumulating on the forward side of said profile during the operation of profiling, in a direction from the apex of said mold towards the periphery thereof, to be intercepted by said trough, a means for introducing water into said trough, a disc in contact with said mold, when the latter is in operative position, to be revolved by said mold, vanes on said disc, extending into said trough, for mixing said material in said trough with said water during the operation of said mold, a lid on said trough, enclosing said vanes therebetween, and a means for conveying said mixture from said trough to a desired destination.

15. In a profiling apparatus a mold with a charge of material thereon, a profile, a helical member for transferring the excess of material, which accumulates on the forward side of said profile, a groove on the forward side of said profile, for housing the rear side of said member, thereby allowing the working edge of the latter to be brought nearer said profile, a casing, for enclosing the forward side of said member, and a means for actuating said member.

16. In a profiling apparatus, a mold, a profile, a trough encompassing the periphery of the mold, means for automatically conveying excess material from the mold to the trough, and means for conveying said excess material from the trough.

17. In a profiling apparatus, a mold, a profile, a trough encompassing the periphery of the mold, means for conveying excess material from the mold to the trough, means for spraying water into the trough, and means for conveying the contents of the trough to a desired destination.

18. In a profiling apparatus, a mold, a profile, an annular trough encompassing the periphery of the mold, the diameter of said trough being of sufficient diameter to accommodate molds of the largest diameter, a deflector disc extending from the mold to the trough, and means for conveying excess material from the mold to the trough.

19. In a profiling apparatus, a mold, a profile, a trough encompassing the periphery of the mold, means for transferring excess material from the mold to the trough, and a channel disposed at a lower elevation than

- said trough and in communication therewith to transfer material from the trough to a desired destination.
20. In a profiling apparatus, a mold, a profile, a trough encompassing the periphery of the mold, means for transferring excess material from the mold to the trough, a channel disposed at a lower elevation than said trough and in communication therewith, and a screw conveyor in said channel. 5
21. In a profiling apparatus, a mold, a profile, means for removing excess material during the operation of profiling, and means for crushing and disintegrating the material removed. 10
22. In a profiling apparatus, a mold, a profile, a trough encompassing the periphery of said mold, means for conveying excess material from the mold to the trough, a channel disposed at a lower elevation than the trough and in communication therewith, a screw conveyor in said channel, and a gear in mesh with said screw conveyor for disintegrating the material delivered to the channel. 15
23. In a profiling apparatus, a mold, a profile, a trough encompassing the periphery of the mold, means for conveying excess material from the mold to the trough, and means for crushing and kneading the material in the trough. 20
24. In a profiling apparatus, a mold, a profile, a trough encompassing the periphery of the mold, means for conveying excess material from the mold to the trough, means for introducing water into the trough, and means for mixing the material and water in the trough. 25
25. In a profiling apparatus, a mold, a profile, a trough encompassing the periphery of the mold, means for conveying excess material from the mold to the trough, means for introducing water into the trough, and a plurality of vanes adapted to be operated so as to mix the water with said material. 30
45. 26. In a profiling apparatus, a mold, a profile, a trough encompassing the periphery of the mold, a deflector disc extending from the mold to the trough, a plurality of vanes on said disc extending into said trough, and means for rotating the disc. 35
27. In a pottery forming machine, the combination with a rotating mold adapted to receive clay in a plastic state, of a profile non-rotatably mounted with relation to the rotating mold and adapted to cooperate therewith to smooth and shape the clay into ware, a conduit member disposed to receive excess material accumulated against the profile during the shaping operation, and means for removing the material from said conduit member. 40
28. In a pottery forming machine, the combination with a rotating mold adapted to receive clay in a plastic state, of a profile non-rotatably mounted with relation to the 45
- rotating mold and adapted to cooperate therewith to smooth and shape the clay into ware, a conduit member disposed transversely of said mold and adapted to receive excess material accumulating against the profile during the shaping operation, and conveying means in said conduit member. 50
29. In a pottery forming machine, the combination with a rotating mold adapted to receive clay in a plastic state, of a profile non-rotatably mounted with relation to the mold and adapted to cooperate therewith to smooth and shape the clay into ware, a conduit member disposed transversely of said mold and provided with an inlet opening into which excess material is forced through rotation of the mold, and means for conveying the excess material from said conduit member. 55
30. In a pottery forming machine, the combination with a rotating mold adapted to receive clay in a plastic state, of a profile non-rotatably mounted with relation to the mold and adapted to cooperate therewith to smooth and shape the clay into ware, a conduit member mounted in cooperative relationship with said profile and provided with an inlet opening into which excess material is forced through rotation of the mold, and a screw conveyor for removing the material as it is forced into the conduit member. 60
31. In a pottery forming machine, the combination with a rotating mold adapted to receive clay in a plastic state, of a non-rotatable profile adapted to cooperate with the rotating mold to smooth and shape the clay into ware, and a conduit member mounted adjacent the profile, the receiving extremity of said conduit being disposed in such manner as to receive the excess material accumulating under pressure against the shaping edge of the profile. 65
